(57) **CLAIM**

The ornamental design for a femoral implant, as shown and described.

DESCRIPTION

FIG. 1 is a top and left perspective view of a femoral implant showing my new design;

FIG. 2 is a bottom and right perspective view of the femoral implant shown in FIG. 1;

FIG. 3 is a front elevation view of the femoral implant shown in FIG. 1;

FIG. 4 is a rear elevation view of the femoral implant shown in FIG. 1;

FIG. 5 is a left-side elevation view of the femoral implant shown in FIG. 1;

FIG. 6 is a right-side elevation view of the femoral implant shown in FIG. 1;

FIG. 7 is a top plan view of the femoral implant shown in FIG. 1; and,

FIG. 8 is a bottom plan view of the femoral implant shown in FIG. 1.

The portions shown in broken lines do not form part of the claimed design.
